UNITED STATES PATENT OFFICE.

JUDSON A. DE CEW, OF NEW YORK, N. Y., ASSIGNOR TO PROCESS ENGINEERS, INCORPORATED, OF NEW YORK, N. Y., A CORPORATION OF NEW YORK.

COOK-TANK.

1,372,123.

Specification of Letters Patent. Patented Mar. 22, 1921.

Application filed April 28, 1920. Serial No. 376,662.

To all whom it may concern:

Be it known that I, JUDSON A. DE CEW, a citizen of the Dominion of Canada, residing at New York, in the county of New York and State of New York, have invented 5 certain new and useful Improvements in Cook-Tanks, of which the following is a specification.

This invention relates to size and soap 10 making, and more particularly to the cookers or cook tanks used therein.

By the use of my invention I am able to cook the rosin and alkali in a much more efficient manner than has hitherto been done.

15 In the drawings, which are to be taken as illustrative of one manner in which my invention may be practised, and in no wise a limiting sense;

Figure 1 is a vertical sectional view 20 through a cook tank provided with a preferred embodiment of my invention,

Fig. 2 is a perspective of Fig. 1 having cut away portions to expose the parts,

Fig. 3 is a side elevation of a deflector.

25 Referring now by reference characters to the drawings, the numeral 1 designates a cooker or cook tank of ordinary construction provided with a steam chamber or coil 2 which may be supported upon lugs 3 in the 30 bottom thereof. Volcanically shaped deflecting member 4 (which perhaps had better be called in the form of a truncated cone) is adapted to be removably inserted in the cook tank and spaced apart from the 35 bottom of the tank as by means of pins 5 attached to the lower portion of deflector or member 4 and socketed into recesses 6. Obviously, other forms of support may be provided and yet obtain the desired result.

40 In operation, the size making materials are placed in the tank and the steam turned into the coils. The heated liquid rises

through outlet *a* owing to expansion and is displaced by the cooler liquid at *b*. The restricted outlet at *a* for the hotter liquid 45 and the tapering inlet for cooler liquid *b* tend to increase the speed of the two currents. By this action a thorough and complete agitation and circulation results, and a column of heated material erupts or bubbles above the level of the material in the tank which is like a volcanic eruption. The circulation of the size prevents it from getting thick and viscous around the coils whereby more size is heated in a given time 55 with the same amount of heating surface. It will be readily apparent that by the use of this deflector, currents of heated and cooler material are kept separate and no interfering eddy currents are produced. Also the 60 currents of liquid are separated, and owing to the restricting walls surrounding the currents, an increase in their speed of travel is produced, resulting in ebullition and increased efficiency of the apparatus. 65

This invention is equally applicable to the soap making industry and the efficiency of the tank makes it possible to cook the soap in a much shorter time than is ordinarily required. 70

What I claim is:

1. In a cook tank, a steam member and a deflector of frusto-conical shape standing on its base directly over the steam member and spaced from the steam member and the tank. 75

2. In a cook tank, a steam member adjacent the bottom of the tank, a deflector substantially frusto-conical in shape, and means for removably spacing the deflector from 80 the steam member.

In testimony whereof I affix my signature.

JUDSON A. DE CEW.
